BARREL BEDDING DEVICE FOR RIFLES

Leon S. Weld, Rochester, N. Y.

Application August 9, 1949, Serial No. 109,258

4 Claims. (Cl. 42—75)

1

This invention relates to firearms generally of the class of rifles, and more particularly to barrel bedding device for rifles.

An object of the invention is to provide a device mounted on the rifle stock which is provided with a saddle adapted to receive the rifle barrel.

Another object of the device is the provision of a resilient mounting for the barrel receiving saddle relative to the rest of the device and to the stock so that the resilient mounting will prevent movement of the barrel when the stock is warped by seasonal weather changes and will also have a dampening effect on vibrations of the barrel caused by firing of the rifle.

A further object of the present invention is the provision of a means for adjusting the tension of the resilient means, and a locking means for securing the device in the adjusted position so that firing of the rifle will not change the adjustment.

Still another object of the invention is to so mount the portion of the barrel near the forward end of the stock so that the barrel will rest on a resilient saddle and will not touch the said forward end of the stock at any point.

Still other objects and advantages will become apparent from the following description of the present invention illustrated in the accompanying drawing in which:

Figure 1 is a sectional view of a preferred embodiment of the device showing its position in the stock and the rifle barrel resting thereon;

Figure 2 is a side elevation of the device shown in Fig. 1 with a part of the stock broken away;

Figure 3 is a sectional view of a modified form of the device.

Similar reference characters represent similar parts in the several figures.

In the use of target rifles best accuracy is obtained when the barrel and receiver assembly are carefully fitted in the stock. The barrel should be so positioned so that it does not come in contact with the stock except at a point just back of the forward end thereof. In mounting the barrel in this manner a certain amount of upward pressure must be maintained against the barrel for best accuracy. This amount of pressure varies with the individual characteristics of the barrel, and when fitting a stock it is not always known just what amount of pressure is required. Furthermore, the pressure exerted will vary as the forward end of the stock warps slightly as seasons change and humidity varies. Such a change in pressure causes a slightly different point of impact of a bullet fired from the gun.

The present device is adapted to eliminate any

2

extreme variation in upward pressure on the barrel and consequently promotes greater accuracy in target shooting. As an ancillary advantage the device affords a dampening effect on vibrations of the barrel caused by firing. In the use of my device the barrel does not touch the forward end of the stock but rests in a V-shaped saddle resiliently positioned in the device. It will be seen therefore that this fact simplifies the fitting of the stock to a marked degree.

In the preferred form of the invention shown in Figs. 1 and 2 the device comprises a metallic sleeve or housing 10 which fits within a vertical opening 11 in the forward end of the wooden stock 12. One end of the sleeve is provided with a peripheral outwardly extending flange 13 which is adapted to rest in a recess 14 adjacent the upper end of the vertical opening 11. The other end of the sleeve has a reduced end portion 15 which is provided with an internally threaded aperture extending from the end of the reduced portion into the interior of the sleeve and is of a diameter less than that of the sleeve. In this manner it will be seen that an internal seat 17 has been provided adjacent the inner end of aperture 16, the use of which will become apparent as the description proceeds.

The periphery of the reduced end portion 15 is threaded to receive a complementary internally threaded dust cap 18, the outer diameter of which is the same as sleeve 10. The head of cap 18 is flanged and provided with an external slot 19 which is adapted to receive therein a screw driver or other similar tool. A further use of cap 18 is to prevent movement of the sleeve in the stock by means of the flange bearing against the wood. The dust cap also improves the general appearance of the device.

Sleeve 10 is adapted to receive therein a coil spring 20, one end of which lies against a metal disc 21 which rests in the seat 17. The other end of the spring extends outwardly beyond the flanged end of sleeve 10. A V-shaped saddle 22 of plastic or other material has projecting downwardly from a central portion thereof a stub shaft 23 which has a diameter slightly less than the internal diameter of coil spring 20 and is adapted to be received therein. The bottom of saddle 22 abuts the upper end of spring 20.

It will be noted that stock 12 is hollowed out as at 24 to receive a portion of the barrel 25, the barrel resting in the V-shaped saddle. Also to be noted is the fact that no part of barrel 25 touches the hollowed out portion of the stock.

The adjustment of the tension of the coil spring

for applying a certain amount of pressure on the barrel is accomplished by an adjusting screw 26 and a locking screw 27 which are inserted in the threaded aperture 16. After screwing the adjustment screw inwardly until it abuts the disc 21 positioned in the sleeve seat 17, further movement of the screw will place the desired tension on spring 20. Screw 27 is then screwed into the aperture until it abuts screw 26 thereby locking the adjusting screw in position.

The installation and operation of the barrel bedding device is very simple. After stock 12 has been provided with the hollowed out portion 24, the seat 14 and the vertical opening 11, sleeve 10 is placed in the vertical opening until flange 13 rests in its seat on the stock. Disc 21 is then inserted into the sleeve followed by the coil spring 20 in which is positioned the V-shaped saddle 22. The next step is to place the barrel 25 in the saddle and secure the barrel to the stock near the butt end thereof (not shown). The tendency will be for the barrel to compress spring 20. The amount of compression desired will depend on the characteristics of the barrel. To vary the compression it is but necessary to move screw 26 vertically. Upon reaching the desired compression the locking screw 27 is moved into contact with screw 26 and the adjustment is secure. The dust cap 18 is utilized to prevent dust from entering aperture 16 and the opening 11.

The modified form of the invention shown in Fig. 3 is adapted to be used with the type of rifle provided with a sling. It will be seen by a careful analogy that the sleeve, coil spring, V-shaped saddle and the screw adjusting and locking means are the same in both the preferred and modified forms of the invention and have been so designated in the figures. In the modified form, however, the reduced end portion of sleeve 10, illustrated as 15', is not furnished with screw threads. Neither is an internally threaded dust cap of the preferred form of the invention included. Instead a dust cap 30 is utilized and is provided at one end thereof with a sleeve-like portion which is adapted to receive the reduced end portion 15' of sleeve 10. The other end portion of the dust cap is tapered downwardly and inwardly as at 32. Near the end of this latter end portion a transversely extending aperture 33 is provided which is designed to slidably receive the free end portions of a swivel eye 34. A second aperture 35 is provided centrally of the cap and is perpendicular to aperture 33. When sleeve 31 is mounted on reduced end portion 15', aperture 35 is in direct alignment with aperture 16 in sleeve 10. A threaded bolt 36, provided with a headed end portion 37, is insertable in aperture 35 and threadingly received by aperture 16 until the bolt abuts locking screw 27, thereby swivelly mounting the cap in position. It is to be noted that a space is provided between the free ends of swivel eye 34 in order that bolt 36 may pass therebetween and maintain the eye in a centralized position. The operation of this modified form of the invention is identical with that of the preferred form as far as support of the barrel is concerned.

From the foregoing detailed description it will be readily apparent that I have provided a barrel bedding device which eliminates any extreme variation in pressure on the barrel and consequently promotes greater accuracy. Any warping or swelling of the wooden stock is substantially absorbed by the coil spring which operates the forward end of the stock and barrel. If the stock

warp to any great degree the tension of the spring will be affected to a greater extent. In this instance it is but necessary to change the position of the adjusting screw until the desired tension is reached. A further advantage which is inherent in my present invention lies in the vibration dampening effect of the spring. After firing the spring always returns the barrel to its normal position and the tension in the spring 10 remains the same.

While a preferred form of the invention has been shown and described and the materials making up the various parts has been recited, it will be understood that variation in details of 15 form and materials may be made without departure from the invention as defined in the appended claims.

I claim:

1. In a rifle including a stock having a barrel 20 mounted thereon and provided with an aperture near one end thereof, a barrel bedding device 25 comprising a sleeve provided at one end thereof with a peripheral flange adapted to rest on the stock adjacent the upper end of said aperture, a spring means positioned in said sleeve having one end thereof extending outwardly beyond the flanged end and the other end resting against a disc in the sleeve, a barrel receiving saddle supported by said spring, said sleeve having at the 30 other end thereof a reduced portion provided with a concentric threaded aperture, adjusting screw means threadingly received by the last-named aperture for contacting the disc in said sleeve and varying the tension of the spring, and 35 dust cap means mounted on the said reduced end portion.

2. In a rifle including a stock having a barrel 40 mounted thereon and provided with an aperture near one end thereof, a barrel bedding device 45 comprising a sleeve provided at one end thereof with a peripheral flange adapted to rest on the stock adjacent the upper end of said aperture, a spring means positioned in said sleeve having one end thereof extending outwardly beyond the flanged end and the other end resting against a disc in the sleeve, a barrel receiving saddle supported by said spring, said sleeve having at the 50 other end thereof a reduced portion provided with a concentric threaded aperture, adjusting screw means threadingly received by the last-named aperture for contacting the disc in said sleeve and varying the tension of the spring, and a dust cap swivelly mounted on the said reduced end portion.

3. A barrel bedding device adapted to be 55 mounted on the forward end of a rifle stock comprising a sleeve having a flange on one end thereof adapted to rest on the stock, a coil spring positioned in the sleeve supporting a barrel receiving saddle, one end of said spring resting on a disc positioned in the sleeve, a recessed end portion on the other end of the sleeve provided with a threaded aperture therein, an adjusting screw received by said aperture and contacting said disc 60 for varying the spring tension, a locking screw received by said aperture adapted to secure the adjusting screw in a desired position, and a swivelly mounted dust cap secured to the said recessed portion.

4. A barrel bedding device adapted to be 65 mounted on the forward end of a rifle stock comprising a sleeve having a flange on one end thereof adapted to rest on the stock, a coil spring positioned in the sleeve supporting a barrel receiving saddle, one end of said spring resting on

a disc positioned in the sleeve, a recessed end portion on the other end of the sleeve provided with a threaded aperture therein, an adjusting screw received by said aperture and contacting said disc for varying the spring tension, a locking screw received by said aperture adapted to secure the adjusting screw in a desired position, and means mounting a swivel eye on the recessed end portion, said means comprising a dust cap having at one end thereof a sleeve-like portion adapted to receive the said reduced end portion, the other end portion thereof tapering inwardly and downwardly and provided with an aperture in alignment with the first-named aperture and adapted to receive a screw means therein for attachment to the sleeve, and a third-named aperture in the tapered portion extending perpendicular to the second-named aperture and positioned near the free end of the tapered por-

tion, said third-named aperture adapted to slidably receive the free ends of the swivel eye therein.
